CLAIM

The ornamental design for a table, as shown and described.

DESCRIPTION

FIG. 1 is a perspective view of a table, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross sectional view taken along the line 8-8 in FIG. 6;

FIG. 9 is a cross sectional view taken along the line 9-9 in FIG. 8; and,

FIG. 10 is a cross sectional view taken along the line 10-10 in FIG. 8.

The broken lines shown in the drawings illustrate portions of the table that form no part of the claimed design.
